CLAIM

An ornamental design for a bottle, as shown and described.

DESCRIPTION

FIG. 1 is a rear elevational view of a bottle embodying my new design;

FIG. 2 is a front elevational view thereof;

FIG. 3 is a side elevational view thereof;

FIG. 4 is a top plan view thereof; and,

FIG. 5 is a bottom plan view thereof.

The broken lines in the figure drawings represent unclaimed environment only and forms no part of the claimed design.

1 Claim, 2 Drawing Sheets
